DESIGN FOR A COFFEEPOT

Frank S. Trumbull, Providence, R. I.

Application July 31, 1935, Serial No. 57,877

Term of patent 3½ years

To all whom it may concern:

Be it known that I, Frank S. Trumbull, a citizen of the United States of America, residing at Providence, county of Providence, State of Rhode Island, have invented a new, original, and ornamental Design for a Coffeepot, of which the following is a specification, reference being had to the accompanying drawing, forming a part thereof.

Fig. 1 is a side elevational view of a coffee pot showing my new design; Fig. 2 is an end elevational view looking at the handle end thereof; and Fig. 3 is an end elevational view looking at the spout end thereof, of the same.

I claim:

The ornamental design for a coffeepot, substantially as shown and described.

FRANK S. TRUMBULL.
